CONTAINER

Richard P. Ware, Detroit, Mich.

Application November 16, 1932, Serial No. 642,907

8 Claims. (Cl. 229—14)

This invention relates to containers and more particularly to shipping containers made of paper or the like, preferably corrugated.

The invention aims to provide a shipping container whose walls are provided with liners which form air spaces against the walls, the container, including its walls and liners, preferably being made from a single blank.

The invention further aims to provide a single blank container having four walls, a top and a bottom, and having, in addition, six flaps, four of which form liners for the four walls, and two of which form liners for the top and bottom respectively.

Still further objects of the invention will become readily apparent upon reference to the following detailed description and drawings of a preferred embodiment of the same. In these drawings:

20 Figure 1 shows the container blank;

Figure 2 is a diagrammatic perspective view of the container, in a completely distended condition;

25 Figure 3 is a diagrammatic perspective view of the container closed, and indicates section planes 4—4, 5—5, and 6—6 corresponding to Figures 4, 5, and 6;

Figure 7 is a cutaway plan view of a corner construction.

30 Referring to the drawings, it will be seen that the container blank is cut from a single sheet of proper size, bounded by the lines connecting the corners 1, 2, 3, 4. The blank is cut from the sheet by any suitable device, for example, a die cutting machine or the like, and is also scored to provide a front wall 10, side walls 11 and 12, a back wall 14, a top 15, and a bottom 16. In the preferred embodiment, top 15 forms an upper extension of side wall 11 and bottom 16 forms a lower extension of back wall 14.

As previously mentioned, the preferred embodiment has four liners for the four walls, and two liners for the top and bottom walls, and these will now be described. The liners for the 45 front and back walls are similar, and are in the nature of flaps 18 and 22, formed as upper extensions of these walls, and provided with spacer portions 19—20, and 23—24, as indicated. The liners for the side walls are also similar, and are also in the nature of flaps 26 and 30, formed as lower extensions of these walls, and provided with spacer portions 27—28, and 31—32, as indicated. The liners for the top and bottom are also similar and are also in the nature 50 of flaps 34 and 40 formed as upper and lower

extensions of the walls 12 and 10, respectively, and provided with three spacer portions 35, 36, 37, and 41, 42, and 43, as indicated.

In forming the blank from the sheet of stock 1, 2, 3, 4, the sheet is positioned in the cutting machine in such a manner that the edges 1, 2, and 3, 4, are engaged by positioning guides. The cutting knives are so arranged that they cut the blank on the following boundary lines: The four part line connecting the upper left 60 hand corner of flap 15 to the upper left hand corner of flap 18; the nine part line connecting the upper right hand corner of flap 18 to the upper left hand corner of flap 22; the two part line connecting the upper right hand corner of flap 22 to the upper right hand corner of flap 14; the one part line connecting the lower right hand corner of flap 16 to the lower left hand corner of the same; the one part line connecting the upper right hand corner of flap 30 to 65 the lower right hand corner of the same; and the eleven part line connecting the lower left hand corner of flap 30 to the lower right hand corner of flap 26. All of the cutting lines are indicated by the letter "c", and in the embodiment disclosed there are twenty-eight separate cutting lines.

The blank is also scored, for folding, on lines indicated by the letter "s", as follows: The two, long, parallel lines connecting edges 1—4 and 85 2—3 of the blank, these two lines being the upper and lower edges of the container walls; the three, short, parallel lines separating walls 11—10, 10—12, and 12—14; the lines defining 90 portions 19 and 20 of flap 18; portions 35, 36, 37 of flap 34; portions 23 and 24 of flap 22; portions 27 and 28 of flap 26; portions 41, 42, and 43 of flap 40; and portions 31 and 32 of flap 30; there being, in the embodiment disclosed, 95 nineteen score lines.

It will be observed at this time that certain of the score lines, indicated by double lines in Figure 1 are in the nature of grooves formed in the top surface of the blank, and that others, namely those four on flaps 34 and 40 separating the major portions of these flaps and their portions 100 37—36, 42—43, are in the nature of grooves formed in the opposite surface of the blank, these score lines, as indicated by the single lines of Figure 1, presenting ridges on the visible surface.

The scoring operation may be performed simultaneously with, or after the cutting operation. In the event it is performed after the cutting operation, the upper edges of flaps 18 and 110

22, and the lower edges of flaps 26 and 30, being aligned as indicated, form guides for the cut blank as it is fed or placed in the scoring device.

Further describing the cut and scored blank, 5 it will be seen that two of the liners, namely, liners 26 and 30, formed as lower extensions of their respective walls, are as wide as the inside of the container, that is to say they are substantially of the same width as the walls from which 10 they extend. The other two wall liners, namely, liners 18 and 22, and the top and bottom lines 34 and 40, are narrower than the walls from which they extend. This dimensioning assures proper 15 cooperation of the parts, as will presently appear.

Further, it will be observed that the scrap stock is only a small percentage of the entire blank, which is of course, a desirable feature.

After the blank is completely cut and scored, 20 as above described, it is preferably provided on a portion of edge 1-4 with a strip of sealing tape or the like, referenced 50. The tape is secured to the invisible surface of the blank on the left hand portion of the side wall 11 and has an extending portion whose visible surface is coated 25 with adhesive, substantially as shown. The blank in this form, with sealing tape 50 attached thereto, may then be folded on the fold lines between walls 11-10, and 12-14, so that wall 14 will overlie wall 12 and wall 11 will overlie wall 30. 10. This brings edges 1-4 and 2-3 into juxtaposition, and the extending portion of the sealing tape is then allowed to overlie the adjacent portion of wall 14 and be adhered thereto, to 35 form a completely fabricated container, ready to be assembled.

It is contemplated, at present, to ship containers from the container factory to the container using establishment, namely, the packer, 40 with the containers in the blank form of Figure 1, leaving the last mentioned operation to be performed in the container using establishment. However, if desired, the last mentioned operation may be performed in the container factory, and 45 the container shipped therefrom to the packer in a partially folded condition, with sealing tape 50 adjoining walls 11 and 14.

In order to set up a container from the folded condition, wherein walls 11 and 14 are joined, 50 it is first necessary to fold the side wall liner flaps 26 and 30 into the container, and upwardly, through arcs of about 180° from the position they occupy in Figure 2, the liners then being positioned to occupy the positions of Figure 4. Portions 27 and 28 of liner 26 will space the latter from wall 11 to form an air space therebetween, and portions 31 and 32 of liner 30 will similarly space the latter from wall 12. Then 55 the bottom wall liner 40 is turned upwardly through an arc of about 90° from the position of Figure 2, to the position of Figure 5, with its portions 41, 42, and 43 serving to locate and seat liner 40 properly. The bottom is then completed by turning bottom wall 16 upwardly from the 60 position of Figure 2, through an arc of about 90°, to the position of Figure 5.

After the lower flaps are turned upwardly, as 70 just described, the front and back wall liners 18 and 22 are folded downwardly and inwardly into the container, from the positions of Figure 2, through arcs of about 180°, to the positions of Figure 5. Their portions 19 and 23, 20 and 24 will locate the liners and space them from walls 10 and 14 to form air spaces adjacent these 75 walls, and their portions 20 and 24 will seat

themselves between the edges of liner 40 and the walls 10 and 14, for similar purposes.

When the four lower flaps are turned upwardly and inwardly, and the two upper flap-side wall liners are turned downwardly and inwardly, there is formed a complete container having an open top through which the container may be loaded, the contents then resting upon the bottom 40, in turn supported by its portions 42 and 43. After the container has 80 been loaded, it may be closed by turning the top liner 34 and the top 15 inwardly to the positions of Figure 4, substantially as indicated. The container may then be sealed in any suitable fashion, not here described specifically.

A novel feature, best disclosed in Figure 7, is the corner construction. As indicated in this figure, the portion 28 of liner 26 is cut off square, and projects to and engages the inside surface of wall 14. The portion 23 of liner 22, however, 85 is miter cut on line 51, and portion 23, extending from wall 14, overlies a corner of portion 28, the net effect being to produce a lap joint at this point which gives the appearance of a miter joint. A similar joint is formed at the upper 100 corner of walls 11 and 10. True miter joints are formed at all other corners and these are not specifically described, other than to mention 105 that they are formed by the indicated notch cutting of liners 26 and 30, these cuttings co-operating with miter cuttings on other liners.

While throughout the foregoing, the container has been described as formed from a single blank, it is apparent that the top and bottom liners may be formed of separate pieces, properly shaped to cooperate with the remaining parts and to form a container similar to the one formed by the blank of Figure 1. In this variation, whereas four of liners will be integral with the walls, two of the liners, namely, the top and 110 bottom liners, will be separate. Further, if desired, the container need not be provided with top and bottom liners at all or may be provided with but one of them, depending upon the desires 115 of the user.

Still further, if desired, the air spaces between the walls and their liners may be provided with an insulating packing, such as for example, cellulose, excelsior pack, etc. These may be placed in the air spaces separately or they might 120 be arranged in one integral and continuous strip long enough to extend along the blank from edge 1-4 to edge 2-3, and as wide as the height of the walls, this form of strip being placed on and glued to the blank of Figure 1 so 125 as to cover walls 10, 11, 12, and 14. Then when the container is set up, the strip of packing is folded along with the walls, and disposes itself in a continuous band of insulation around the inside of the walls of the container.

It will be observed at this time that when a strip of packing is laid along the portions 11-10-12-14 of the blank, and adhesively secured thereto, as is at present contemplated, 130 portions of the strip, adjacent the container corners, will be crushed when the blank is folded. For this reason, it would be well to cut away the right hand edge of liner 26 and the left hand edge of liner 30, to narrow these liners and permit clear spaces to be formed near the container 135 corners, these spaces then permitting the strip of packing to curve itself around the inside of the container, near the corners, without its being crushed.

The container disclosed facilitates the adop- 140

tion of a new process of refrigeration, now to be described. A manufacturer of solidified CO₂ may ship a sealed unit, consisting of the container and a block of CO₂, to a consumer, who then places the unit, container and all, in a refrigerator. The container might well be provided with a number of partially scored but normally sealed openings, any desired number of which may be opened to permit escape of CO₂. 10 gas, the number depending upon the desired rate of refrigeration. The container permits the solidified CO₂ to be shipped, without appreciable deterioration or diminution, and also permits the block of CO₂ to be placed in the refrigerator, 15 without there being a possibility that the consumer can be injured by manual or bodily contact with the naked block of CO₂. The container cutouts or openings permit of a variation of the refrigeration rate. This process is believed to be 20 novel and is facilitated by the efficient and practical container disclosed and herein claimed.

Further if desired, the bottom and/or the top liner may have holes punched therein to form seats for contained products, such as bottles or 25 the like. These holes may be formed when the blank is cut and their provision entails no considerable expense. Further, if desired, especially where the container is used to ship a commodity such as solid carbon dioxide, or 30 where it is used to ship refrigerated products, holes may be provided in certain of the liners to assist in the circulation of air, wherever circulation is desired. In that event, the gas given off by the carbon dioxide will pass through the 35 holes and into the spaces between the liners and the walls, to fill these walls with the gas and thus to form gas filled insulating chambers.

Further if desired, the top and bottom liners may be provided with portions extending from 40 portions 37 and 43 to engage portions 28 and 24 there adjacent, and thus to limit the inward movement of the top and bottom liners.

Further, if desired, the container may be used 45 as a multi-cell container wherein one cell contains a refrigerant and the other contains contents to be refrigerated. For example, the container may be used to ship ice cream, in which case, small blocks or the like of solid carbon dioxide, might be placed in the bottom space, 50 between liner 40 and the bottom 16, the ice cream being placed in the interior of the container, on top of liner 40. The refrigerant may then be placed in its compartment, which may then be sealed, and then ice cream may be placed 55 in the interior of the box and the top sealed. In order to get at the ice cream, then, the user would not have to come in contact with the refrigerant, but may get at the ice cream merely by opening the container top.

The container might also be used for shipping 60 fruits, or the like. The liners would thus prevent outside shocks from reaching the contained products, and the air spaces adjacent the liners 65 would serve to insulate the contained products from outside weather conditions.

The container might also be used to ship 70 delicate articles, such as radio sets, lamps, etc., the liners serving to insulate the contents from shocks against the walls of the containers.

From the foregoing, it will be observed that 75 there has been provided a novel shipping container, characterized, by its having air-space forming liners for four or more walls, the liners and the walls being integrally formed from a

single blank, without complications or difficulties of manufacture.

Now having described a preferred embodiment of the invention, reference will be had to the following claims, for a determination of the scope of the same, it being understood that the invention is not to be limited to the construction chosen by way of example, but is to be determined by the claims which follow:

1. A container including a plurality of relatively connected enclosing walls having liners covering substantially their entire aggregated area, the liners being integral with and being in the nature of inwardly folded flaps extending from the walls, the container further including two tops and two bottoms integral with the aforementioned walls and being in the nature of folded flaps extending from the walls. 85

2. A container including a plurality of relatively connected enclosing walls having liners covering substantially their entire aggregated area, the liners being integral with and being in the nature of inwardly folded flaps extending from the walls, the container further including two tops and two bottoms integral with the aforementioned walls and being in the nature of folded flaps extending from the walls, half of the flaps extending from lower wall edges and half of the flaps extending from upper wall edges. 90

3. In a container blank, a row of relatively connected enclosing walls, wall liner flaps extending from lower wall edges and foldable to form liners for the walls and dimensioned to cover substantially the entire areas of their respective walls, and similarly foldable and dimensioned wall liner flaps extending from upper wall edges, there being at least four walls, two upper wall liner flaps, and two lower wall liner flaps, no two of the wall liner flaps extending from the same wall, the blank further having a top flap extending from an upper wall edge, and a bottom flap extending from a lower wall edge, the blank further having a top liner flap extending from an upper wall edge, and a bottom liner flap extending from a lower wall edge. 105

4. A single blank container including a plurality of vertical enclosing walls, vertical liners therefor formed as flaps extending from horizontal edges thereof, horizontal walls formed as flaps extending from horizontal edges of said vertical walls, and horizontal liners for said horizontal walls, and also formed as flaps extending from horizontal edges of said vertical walls. 110

5. A single blank container including a plurality of vertical enclosing walls, vertical liners therefor, horizontal walls, and horizontal liners for said horizontal walls, all the liners and said horizontal walls, being formed as flaps extending from horizontal edges of said vertical walls. 115

6. A single blank container including a plurality of vertical enclosing walls, vertical liners therefor, horizontal walls, and horizontal liners for said horizontal walls, all the liners and said horizontal walls, being formed as flaps extending from horizontal edges of said vertical walls, each liner flap including two spacer portions between which is a liner proper portion. 120

7. A single blank container including a plurality of vertical enclosing walls, vertical liners therefor, horizontal walls, and horizontal liners for said horizontal walls, all the liners and said horizontal walls, being formed as flaps extending from horizontal edges of said vertical walls, the horizontal outer and free edges of adjacent 125

wall liner flaps, when the container is in blank form, being in alignment to assist in guiding the blank in a blank-processing machine.

8. A single blank container including a plurality of enclosing, vertical side walls, a pair of flaps extending from opposite edges of each

wall, one and one only of the flaps of a pair forming a liner for said wall when the container is folded, the other flap of the pair forming a horizontal closure part connecting opposite vertical side walls.
